Inventor:
Isaac Bein,
By his Attorney, Geo. M. Misch

UNITED STATES PATENT OFFICE.

ISAAC BEIN, OF NEW YORK, N. Y.

WINDOW-SASH-SECURING MEANS.

Application filed April 14, 1924. Serial No. 706,368.

To all whom it may concern:

Be it known that I, ISAAC BEIN, a citizen of the United States, residing in the borough of Manhattan, city, county, and State 5 of New York, have invented certain new and useful Improvements in Window-Sash- Securing Means, of which the following is a specification sufficient to enable those skilled in the art to which the invention app- 10 pertains to utilize the same.

The object of my invention is the provi- sion of means whereby the upper and lower sashes of windows may be effectually se- cured together in various co-relative posi- 15 tions, so that either or both sashes may be positively adjusted to a prescribed or de- sired extent or area of opening, and to this end the invention consists in the specific construction, combination and arrangement 20 of parts and appurtenances described and claimed, distinctive features being the au- tomatic action of the bolt in the locking and un- locking operations, and the use, in con- junction therewith, of a release key, all as 25 hereinafter fully set forth.

In the accompanying drawings I illus- trate a practical embodiment of the essen- tial features of my improvements in window sash securing means, although I do not limit 30 myself to the identical form and construc- tion of parts shown by way of exemplification, since modifications in minor details and equivalent mechanical expedients may be resorted to with like results and without 35 departing from the spirit and intent of my invention in this respect.

With this understanding:—

Fig. 1, represents adjacent portions of up- 40 per and lower window sashes secured to- gether by my locking device;

Fig. 2, is a sectional elevation taken upon plane of line 2—2 Fig. 1;

Fig. 3, is a central vertical sectional ele- 45 vation, upon an enlarged scale, of my im- proved sash securing mechanism, the parts being shown in locked position;

Fig. 4, is a transverse section taken upon plane of line 4—4 Fig. 3;

Fig. 5, is a view like unto Fig. 3, show- 50 ing the operative parts in released position;

Fig. 6, is a face view of a mortise plate suitable for use in conjunction with my im- proved sash lock mechanism;

Fig. 7, is what may be designated as a 55 top view, approximately actual size of the

bolt slide member of my sash securing means;

Fig. 8, is an elevation thereof taken at right angles to Fig. 7;

Fig. 9, is a central longitudinal section of 60 the barrel or casing.

Fig. 10, is a front end elevation thereof;

Fig. 11, is an elevation of the inner side 65 of the latch;

Fig. 12, is a sectional elevation taken up- 70 on plane of line 12—12 Fig. 11;

Fig. 13, is an exterior elevation of my de- 75 vice when the operative parts are in the position shown in Fig. 5;

Figs. 14 and 15, represent transverse sec- 80 tional elevations taken upon plane of line 14—14, Fig. 8, illustrating the operative action of the key in disengaging the latch from the inturned abutment of the casing.

M, is a mortise plate to be secured to the 85 side of one of the sashes, preferably the up- per one S, as indicated in Figs. 1 and 2 of the drawings, my locking device being mounted on the other sash S', and the lock- ing device to the upper sash S, if preferred, the results attainable being essentially the same in either case. That is to say, the bolt b^x, may be made to engage with any of the mortise holes m, m, in said plate M, as may be found most expedient.

C, is a cylindrical casing, contracted at its 90 inner end to form the central bolt aperture c, and formed at its outer extremity with the annular flange c', having countersunk holes c², c² for the accommodation of the attach- 95 ing screws c³, c³, shown in Fig. 1. The cas- ing C, is also formed with an inturned abut- ment tongue or shoulder c^x, and with a lon- 100 gitudinal slot c⁴, for the accommodation of a screw stub b, which is protuberant from the bolt slide B, whereby the latter is held against rotative movement on its longitu- 105 dinal axis while reciprocable within pre- scribed limits within the casing C, as will be understood by a comparative reference 100 more particularly to Figs. 3 and 5 of the drawings. This screw stub b, also func- tions as a means of adjustment between the bolt slide B, and the casing C, since it pre- vents the withdrawal of said slide B, from 105 said casing C, while admitting of the manip- 110 ulation of the slide.

The bolt b^x, is formed integral with the inner end of the slide B, while the forward extremity of said slide B, is formed with an 110

integral spindle stud b' , on which is rotatably mounted the manipulative handle or knob K, formed with a key slot k.

Pivots on one side of the spine 5 portion of the bolt slide B, is a spring latch L, the spring l, of which tends constantly to hold said latch L, in engagement with the abutment c^x , of the casing C. A coil spring a, is interposed between the inner end of the 10 casing C, and the body of the bolt slide B, surrounding the bolt b^x , as shown more particularly in Figs. 3 and 5 of the drawings.

In operation, the parts being in the position shown in Fig. 5, when the bolt slide is 15 pressed inward by means of the knob K, and against the resistance of the coiled spring a, the latch L, automatically springs into engagement with the rear edge of the abutment c^x , as shown in Fig. 3, thereby holding 20 the bolt b^x , in engagement with a mortise m, of the plate M, as indicated in Fig. 2, of the drawings.

When the latch L, is released from the 25 abutment c^x by means of a key inserted through the slot k, of the manipulative knob K, the latter being turned on the spindle stud b' , to effect this result, the spring a, returns the parts automatically to the position shown in Fig. 4, of the drawings.

In Figs. 1 and 2 of the drawings my securing means are shown as holding to sashes S', S'', in closed relationship, although it is obvious that the sashes may be held apart at 30 various distances and elevations, by resort to the different mortise holes m, in the plate M, and hence that the area of window opening may be adjusted to requirements while 35 insuring safety in that the sashes cannot be released except in a prescribed manner by 40 means of a key inserted through the manipulative knob K, of the bolt slide B, as hereinbefore set forth. Obviously, therefore, ventilation may be attained with safety,

since ingress and egress through the window thus protected will be prevented to an extent 45 that would preclude accident from within or intrusion from without.

What I claim as my invention and desire to secure by Letters Patent, is:—

1. Window sash securing means of the 50 character designated, comprising a casing formed with an inner abutment and with a longitudinal slot, a bolt slide mounted in said casing and formed with an integral bolt at one extremity, and an integral spindle stud at its other extremity, a coil spring interposed between said bolt slide and the inner end of the casing, a rotatable manipulative knob mounted on said spindle stud, and formed with a key slot, a screw stud 55 on the bolt slide extending through said longitudinal slot in the casing, and a spring latch mounted on said bolt slide for engagement with said abutment on the casing, substantially in the manner and for the purpose set forth.

2. Window sash securing means of the 60 character designated, comprising a casing formed with an inner abutment and with a longitudinal slot, a bolt slide mounted in 70 said casing and formed with an integral bolt at one extremity, and an integral spindle stud at its other extremity, a coil spring interposed between said bolt slide and the inner end of the casing, a rotatable manipulative knob mounted on said spindle stud, and formed with a key slot, a screw stud on 75 the bolt slide extending through said longitudinal slot in the casing, and a spring latch mounted on said bolt slide for engagement with said abutment on the casing, and in combination therewith a mortise plate formed with a plurality of mortises for engagement with said bolt, substantially in 80 the manner and for the purpose set forth.

ISAAC BEIN.
